CLAIM

The ornamental design for a USB type-C receptacle, as shown and described.

DESCRIPTION

FIG. 1 is an isometric view of the USB type-C receptacle; FIG. 2 is another isometric view of the USB type-C receptacle;

FIG. 3 is a front view of the USB type-C receptacle;

FIG. 4 is a left side view of the USB type-C receptacle;

FIG. 5 is a right side view of the USB type-C receptacle;

FIG. 6 is a back view of the USB type-C receptacle;

FIG. 7 is a top view of the USB type-C receptacle; and,

FIG. 8 is a bottom view of the USB type-C receptacle.

In the drawings, the evenly spaced broken lines are for the purpose of illustrating portions of the USB type C receptacle that form no part of the claimed design.

1 Claim, 8 Drawing Sheets
